J. B. HADAWAY

CUSHION HEEL BLANK

Filed Dec. 18, 1922

Fig.1.

Fig.2.

INVENTOR.

John B. Hadaway.

UNITED STATES PATENT OFFICE.

JOHN B. HADAWAY, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

CUSHION-HEEL BLANK.

Application filed December 18, 1922. Serial No. 607,661.

To all whom it may concern:

Be it known that I, JOHN B. HADAWAY, a citizen of the United States, residing at Swampscoot, in the county of Essex and State of Massachusetts, have invented certain Improvements in Cushion-Heel Blanks, of which the following description, in connection with the accompanying drawings, is a specification, like reference characters on the drawings indicating like parts in the several figures.

This invention relates to heel blanks and has in view the production of a cushion heel blank which is readily applicable to shoes as produced under ordinary factory conditions, without the necessity of stocking an excessive, and therefore, prohibitively expensive, variety of sizes and shapes of such blanks.

According to the present practice great care is taken to produce rubber and like cushion heels molded accurately to the size and shape which it is desired that they shall have in the finished shoe. Under shoe factory conditions, however, it is impracticable, if not impossible to make the heel seat portions of all shoes of a given size and style absolutely identical. There is always more or less variation between individual shoes and, therefore, a heel blank which will properly fit one shoe will not exactly fit another. Furthermore, the average shoe factory makes a large variety of shoes, the heel seats of which, many times differ only slightly in size or shape. This condition calls for the maintenance of a large stock of rubber heels, including a great variety of sizes and shapes which differ but little from each other.

By the present invention a heel blank is provided which is readily applicable to shoes, the heel seats of which differ materially in size or shape, or both. It thus becomes possible to use one given size of heel blank to meet requirements which heretofore have called for a multiplicity of heels of different sizes and shapes.

This is accomplished by the provision of a cushion heel blank having a resilient tread portion, the size and contour, or shape, of the outer face of which are those desired in the finished shoe, and a body portion of indeterminate size enough larger than the fin-

ished tread face to permit said body portion, after attachment to a shoe having a heel seat of any one of a variety of different sizes and contours, to be trimmed to a size and shape determined by the counter portion of the heel end of the shoe and the finished tread face of the heel blank. The breast face of the blank may be molded to the final form which it is to have in the finished shoe, eliminating the necessity for any breasting operation. In the illustrated embodiment of the invention the heel blank is a molded rubber unit, the thread portion of which is comparatively soft and resilient, the base portion of the heel body being harder than the resilient tread portion and constituting an anchorage for attaching nails.

A heel of this form is readily trimmed with heel trimming machines in commercial use, the tread faces of all the heels resulting from the use of a given size and shape of blank being uniform in the finished shoes and the base portions of all the heels fitting perfectly the heel seats of the respective shoes to which they have been applied.

A more complete understanding of the features and advantages of the invention will be had from reading the following detailed description of one satisfactory embodiment thereof, in connection with the accompanying drawings, in which—

Figure 1 is a perspective of a cushion heel blank constructed in accordance with the invention; and

Fig. 2 is a cross sectional view of the heel blank attached to a shoe and partially trimmed, the section being taken along the line 2—2.

Referring now to the drawings, the illustrated heel blank has a tread portion 10 the face of which is of exactly the size and shape desired in the finished shoe and a larger body portion 12 which is of the same general shape as the tread portion 10 but of indeterminate size, it only being necessary that it be large enough to provide sufficient material to be trimmed off to produce the desired size and shape in the finished heel.

The heel blank may be produced by the process of vulcanization in a suitable mold and may comprise either a soft resilient tread portion 10 and a harder base portion 14, as

indicated in the drawings, or it may be composed of the same grade of rubber throughout. In any event, the blank will be integral, or unitary, the soft and hard portions of the heel shown in the drawings being vulcanized together.

A heel such as that illustrated is handled and attached as a unit and may easily be nailed with ordinary commercial heelers 19 machines. As shown, the attaching nails 16 are driven through the soft rubber tread portion 10 until their heads are about flush with the junction plane between the soft portion 10 and the hard portion 14, their 15 points passing through the outer sole 18 and being clinched in the inner sole 20 of the shoe. One advantage of utilizing a hard base portion is that it may be nailed down very tightly, to the heel seat of the 20 shoe, affording a very secure attachment for the heel.

Corrugated spots 22 or other suitable indications may be provided to designate the desired locations for the nails and to obliterate the slight mark which is left after the 25 nails are driven through the rubber.

Referring now to Fig. 2 which shows the heel attached to a shoe and partially trimmed, the solid line at the left represents 30 the final edge face of the trimmed heel, the dotted lines 24 indicating the original, unfinished contour of the blank which, it will be observed, is symmetrical with the solid lines at the right of the figure, showing the 35 portion of the heel which has not yet been reached by the trimming cutter, it being understood that the heel trimming machine is provided with gages against which the counter portion of the shoe and the edge of 40 the heel adjacent to its tread face are guided in making the trimming cut.

The breast face of the heel is indicated generally by the reference numeral 26 and may advantageously be formed to its final 45 surface in the vulcanizing mold in which the heel is manufactured, with the result that no separate breasting operation upon the heel is required after its attachment to a shoe.

50 The surface 28 joining the finished edge of the tread portion 10 and the lateral face of the body portion 12 is herein shown as sloping but this is not a matter of importance, inasmuch as this surface will be entirely removed in the operation of finishing the heel.

Having described the invention, what is

claimed as new and desired to be secured by Letters Patent is:—

1. As an article of manufacture, an unattached cushion heel blank having a tread portion of resilient material of a fixed size and shape desired in the finished shoe, and a body portion integral with the tread portion, of intermediate size and shape enough 65 larger than said tread portion to permit the body portion of the heel, after attachment to a shoe of indeterminate size and shape, to be trimmed to a size and shape determined by the heel end of the shoe and said fixed 70 tread portion of the heel blank.

2. An unattached, integral cushion heel blank of molded rubber having a contour at and adjacent to its tread face which is that desired in the finished shoe, and a materially 75 larger body portion, applicable to shoes having heel seats of different sizes and contours, said tread contour and the counter portion of the shoe constituting guides to which the heel body may be trimmed, after attachment 80 to a shoe, to determine its final size and contour.

3. An unattached integral cushion heel blank of molded rubber comprising a resilient tread portion having a contour at and 85 adjacent to its tread face which is that desired in the finished shoe, and a materially larger body portion, applicable to shoes having heel seats of different sizes and contours, the base portion of the heel body being 90 harder than the resilient tread portion, said harder base portion constituting an anchorage for attaching nails, and said tread portion and the counter portion of the shoe constituting guides to which the heel body 95 may be trimmed, after attachment to a shoe, to determine its final size and contour.

4. As an article of manufacture, an unattached, unfinished cushion heel blank having the entire breast face which it is to have in 100 the finished shoe, a resilient tread portion of the size and contour desired in the finished shoe, and a body portion of indeterminate size and shape enough larger than said tread portion to permit the lateral surface of said 105 body portion, exclusive of the breast face, to be trimmed, after attachment of the heel to a shoe, to a size and shape determined by the counter portion of the shoe and said tread portion of the heel blank.

In testimony whereof I have signed my name to this specification.

JOHN B. HADAWAY.

indicated in the drawings, or it may be composed of the same grade of rubber throughout. In any event, the blank will be integral, or unitary, the soft and hard portions of the heel shown in the drawings being vulcanized together.

A heel such as that illustrated is handled and attached as a unit and may easily be nailed with ordinary commercial heelers machines. As shown, the attaching nails 16 are driven through the soft rubber tread portion 10 until their heads are about flush with the junction plane between the soft portion 10 and the hard portion 14, their points passing through the outer sole 18 and being clinched in the inner sole 20 of the shoe. One advantage of utilizing a hard base portion is that it may be nailed down very tightly, to the heel seat of the shoe, affording a very secure attachment for the heel.

Corrugated spots 22 or other suitable indications may be provided to designate the desired locations for the nails and to obliterate the slight mark which is left after the nails are driven through the rubber.

Referring now to Fig. 2 which shows the heel attached to a shoe and partially trimmed, the solid line at the left represents the final edge face of the trimmed heel, the dotted lines 24 indicating the original, unfinished contour of the blank which, it will be observed, is symmetrical with the solid lines at the right of the figure, showing the portion of the heel which has not yet been reached by the trimming cutter, it being understood that the heel trimming machine is provided with gages against which the counter portion of the shoe and the edge of the heel adjacent to its tread face are guided in making the trimming cut.

The breast face of the heel is indicated generally by the reference numeral 26 and may advantageously be formed to its final surface in the vulcanizing mold in which the heel is manufactured, with the result that no separate breasting operation upon the heel is required after its attachment to a shoe.

The surface 28 joining the finished edge of the tread portion 10 and the lateral face of the body portion 12 is herein shown as sloping but this is not a matter of importance, inasmuch as this surface will be entirely removed in the operation of finishing the heel.

Having described the invention, what is

claimed as new and desired to be secured by Letters Patent is:—

1. As an article of manufacture, an unattached cushion heel blank having a tread portion of resilient material of a fixed size and shape desired in the finished shoe, and a body portion integral with the tread portion, of intermediate size and shape enough larger than said tread portion to permit the body portion of the heel, after attachment to a shoe of indeterminate size and shape, to be trimmed to a size and shape determined by the heel end of the shoe and said fixed tread portion of the heel blank.

2. An unattached, integral cushion heel blank of molded rubber having a contour at and adjacent to its tread face which is that desired in the finished shoe, and a materially larger body portion, applicable to shoes having heel seats of different sizes and contours, said tread contour and the counter portion of the shoe constituting guides to which the heel body may be trimmed, after attachment to a shoe, to determine its final size and contour.

3. An unattached integral cushion heel blank of molded rubber comprising a resilient tread portion having a contour at and adjacent to its tread face which is that desired in the finished shoe, and a materially larger body portion, applicable to shoes having heel seats of different sizes and contours, the base portion of the heel body being harder than the resilient tread portion, said harder base portion constituting an anchorage for attaching nails, and said tread portion and the counter portion of the shoe constituting guides to which the heel body may be trimmed, after attachment to a shoe, to determine its final size and contour.

4. As an article of manufacture, an unattached, unfinished cushion heel blank having the entire breast face which it is to have in the finished shoe, a resilient tread portion of the size and contour desired in the finished shoe, and a body portion of indeterminate size and shape enough larger than said tread portion to permit the lateral surface of said body portion, exclusive of the breast face, to be trimmed, after attachment of the heel to a shoe, to a size and shape determined by the counter portion of the shoe and said tread portion of the heel blank.

In testimony whereof I have signed my name to this specification.

JOHN B. HADAWAY.

It is hereby certified that in Letters Patent No. 1,538,036, granted May 19, 1925, upon the application of John B. Hadaway, of Swampscott, Massachusetts, for an improvement in "Cushion-Heel Blanks," errors appear in the printed specification requiring correction as follows: Page 1, line 66, for the word "thread" read *tread*; page 2, claim 1, line 65, for the word "intermediate" read *indeterminate*; and that the said Letters Patent should be read with these corrections therein that the same may conform to the record of the case in the Patent Office.

Signed and sealed this 27th day of October, A. D. 1925.

[*Initials*]

KARL FENNING,
Acting Commissioner of Patents.

UNITED STATES PATENT OFFICE
CERTIFICATE OF CORRECTION

It is hereby certified that in Letters Patent No. 1,536,036, granted May 19, 1925, upon the application of John B. Hadaway, of Swampscott, Massachusetts, for an improvement in "Cushion-Heel Blanks," errors appear in the printed specification requiring correction as follows: Page 1, line 66, for the word "thread" read *tread*; page 2, claim 1, line 65, for the word "intermediate" read *indeterminate*; and that the said Letters Patent should be read with these corrections therein that the same may conform to the record of the case in the Patent Office.

Signed and sealed this 27th day of October, A. D. 1925.
